UNITED STATES PATENT OFFICE.

WARREN A. DURRIN, OF HERSEY, ASSIGNOR, BY DIRECT AND MESNE ASSIGNMENTS, TO JAMES D. HILL, OF MENOMONEE, AND NOAH SHAW, OF EAU CLAIRE, WISCONSIN.

CHAIN.

SPECIFICATION forming part of Letters Patent No. 393,061, dated November 20, 1888.

Application filed March 16, 1888. Serial No. 267,307. (No model.)

To all whom it may concern:

Be it known that I, WARREN A. DURRIN, a citizen of the United States, residing at Hersey, in the county of St. Croix and State of Wisconsin, have invented certain new and useful Improvements in Chains; and I do hereby declare the following to be a full, clear, and exact description of the invention, such as will enable others skilled in the art to which it applies to make and use the same.

My invention consists in an improved construction of a locking-link between each pair of ordinary chain-links, whereby increased strength and durability with reduction of weight and cost of manufacture are secured and a chain is produced having spaces between its locking-links of size adapted for the admission of teeth of driving sprocket-wheels of a thickness and strength sufficient for withstanding the great strain to which they are subjected while driving the chain.

In the accompanying drawings, Figure 1 is a plan view of a chain constructed in accordance with my invention. Fig. 2 is a view showing in central section one of the improved locking-links and in side elevation three ordinary chain-links and three of the improved locking-links. Fig. 3 is a plan, and Fig. 4 a vertical longitudinal section illustrating a modified construction of the invention. Fig. 5 is a section in the line $x-x$, and Fig. 6 a section in the line $y-y$, of Fig. 4. Fig. 7 is a vertical longitudinal section showing another modified construction of the invention and illustrating its use in connection with a sprocket-wheel.

In the accompanying drawings, A A represent ordinary sprocket-links of nearly a square form and rounded on their inner and outer corners. Any other suitable form of chain-links may be adopted.

B are locking-links between the links A A. The locking-links shown in Figs. 1 and 2 are respectively constructed of a link portion, a , an abutting and supporting portion, b , a tie-clamping portion, c , and a rivet, d . The portions a and b are provided with a vertical central passage for the rivet d to pass through them. The link portion a has an opening, a' , between its ends for

the admission into it of the closed ends of the links A A. The abutment and supporting portion b is of an inverted-T shape, and is slipped sidewise into the link portion a , its smaller or body part, b' , passing through the opening a' , while its larger or inverted head part, b'' , passes through the space inclosed by the link below said opening a' , the upper and under side of its head part bearing firmly against the inner upper and lower surfaces of the said link portion a , and thus supporting the link portion, as shown. The ends of the inverted head part b'' of the portion b form the abutments for the links A A, and they are provided with segmental recesses b^3 , so as to fit the curved cross-sectional form of the links A A and allow a free movement of the said links upon the link portion a , while to give lightness the under surface of the inverted head part may be hollowed out, as at b^4 . The body portion b' of the portion b is made shorter than the thickness of the metal of which the link portion a is made, in order that the portions a b c may be compressed slightly, and thereby closely bound upon each other during the act of riveting them together. The tie-clamping portion c is formed with ribs c' , while the link portion a is formed with grooves c^2 on its upper surface for the reception of the ribs c' . The tie-clamping portion is adjusted to the position shown after portion b has been slipped to its proper place, and then the rivet d is inserted through all of the portions and the whole riveted together, and by this riveting operation the portions will be firmly bound together, and yet the links A A left free to articulate upon the open-link portion a .

In Figs. 3, 4, 5, and 6 I have shown that the body part b' of the abutment and supporting portion b can be made longer than the thickness of the metal of the link portion a , and formed with a tapered extension, b^5 , and that the tie-piece c may be grooved at c^6 to receive the extension b^5 , and formed with riveting-ribs c^6 , while the link portion a is formed with matching grooves a^6 , the ribs and extensions of the said parts projecting beyond the sides of the link portion a , as well as beyond the portions b and c , as shown at c^7 b^6 , and when

the said portions and the links A A are brought together in substantially the same manner as hereinbefore described with respect to the construction shown in Figs. 1 and 2, and 5 the projecting ends c' b' being upset, the whole is thereby riveted together, so as to leave the links A A free to articulate on the link portion a of the locking-link B.

In Fig. 7 the locking-link is shown with its 10 portion designated by b and c in Fig. 2 as changed in shape and formed in one piece, as C, and provided with grooves d' for rivets d' to pass through, and constructed to under and over lap the ends of the portion a at the opening a', while it bears against the lower inner surface of the portion a. The rivets d' are 15 passed through the grooves d', and are upset or riveted against the sides of the portions a and C, as illustrated by the dotted circles d', 20 which indicate the upset portions.

What I claim is—

1. The combination, with chain-links, of the locking-link portion a, having an opening, a', the solid abutment and supporting portion b, of inverted-T form, one portion fitting in the 25 opening a' and the other being within the locking-link, the tie-clamping portion c, and the fastening for holding the parts together, all in the manner and for the purpose described.

2. Locking-link B, comprising the link portion a, having an opening, a', the solid abutment and supporting portion b, the tie-clamping portion c, and the rivet d, all riveted together upon the chain-links A A, substantially as and for the purpose described. 30

In testimony whereof I affix my signature in presence of two witnesses. 35

WARREN A. DURRIN.
